BRUSH PRESERVING CASE

Filed March 13, 1931

Inventor:
Richard Kamm.

By J. Daniel Stowe Atty.

UNITED STATES PATENT OFFICE

RICHARD KAMM, OF CHICAGO, ILLINOIS

BRUSH PRESERVING CASE

Application filed March 13, 1931. Serial No. 522,842.

This invention relates to new and useful improvements in a brush preserving case.

One of the main objects of this invention is to provide efficient means for preserving a brush, such as a paint brush or the like, which has the paint or similar material retained in its bristles; whereby to prevent stiffening of the paint and the bristles, and to obviate the troublesome task of cleaning the paint from the bristles every time the brush is to be laid aside.

Another object is to provide a case or container means for enclosing the bristle portion of a paint brush or the like, substantially air-tight; so as to preserve said bristle portion, even though the paint is retained therein, and keep the bristles soft and pliable, for a very long time.

A further object is to provide means for preserving a brush, like a paint brush, for an extended length of time, which means is very simple in construction and economical in manufacture, and is highly efficient in use.

Various other objects and advantages will become apparent from the following description taken in connection with the accompanying drawing, in which the invention is shown in its preferred form, it being understood that other arrangements and forms of construction may be resorted to for carrying out the objects and purposes of this invention.

In the drawing:

Fig. 1 is a perspective view of a brush preserving case embodying this invention in its preferred form of construction.

Fig. 2 is a longitudinal vertical sectional view thereof.

Fig. 3 is a vertical cross-sectional view thereof, taken on line 3—3 of Fig. 2.

The invention is disclosed in this application in the form of a case or container which comprises several members hingedly connected, for housing and preserving substantially air-tight therein the bristle portion of

a brush, as a paint brush or the like. The case or container is made in the several sizes and shapes required to suit the several forms of paint brushes usually employed in this trade.

In the drawing this invention is illustrated in its preferred form of construction, in the shape of a case or container arranged for housing and preserving a flat paint brush therein. This case is therefore made substantially wedge-shaped, to suit the flat brush; and it comprises an upper member 6 and a lower member 7, containing respectively, a top wall 8 and a bottom wall 9, which are substantially flat, and wherefrom extend the side walls 10 and 11, and the end walls 12 and 13, respectively. These side and end walls are arranged to overlap for a considerable distance, and the side walls are substantially triangular in shape in this form of construction.

The two members are hinged together at their thin ends, providing the thin end or wedge end of the case, for receiving the outer end or thin end of the bristle portion of the brush therein. The hinge means preferably includes curled ears 14 and 15, formed integral on the ends of the top wall and bottom wall, 8 and 9, respectively, and having a pivot pin 16 extending therethrough, substantially as indicated in Fig. 1 of the drawing.

The end walls 12 and 13, which are positioned on members 6 and 7 at the ends opposite said curled ears 14 and 15, are provided with notches 18 and 19 respectively; whereby is formed an opening 20, for receiving and closely fitting the handle 21 of a brush which has its bristle portion 22 enclosed in said case and has the handle extending outward thereof, as indicated in Fig. 2.

Pliable or compressible means 23, which may be felt or rubber, preferably in strip form, is preferably also placed between the walls of the two members, to provide a more

perfect air-tight closure between said two members. For this purpose the edge portions of the side walls and the end wall of one of said members, are arranged to form channel means for retaining said compressible means 23 therein; and this is preferably accomplished by doubling over said edge portions, as shown at 24 in the drawing, and then curving the material back to 5 form channel means 25, wherein the compressible strip means 23 is securely clamped. The strip means 23 is folded over beyond the edge portions or edge means of the walls whereon it is mounted, and extends and is compressed 10 between said walls and the overlapping walls of the other member, substantially as shown in the drawing. Similar compressible means 15 26 is preferably also secured along the notch portion of the other member, for firmly bearing 20 upon the brush handle, so that the handle is firmly clasped within said opening 20; and the entire case is thus rendered substantially air-tight to preserve the brush therein.

The brush with the paint thereon may 25 preferably also be first wrapped in waxed paper, before enclosing in this case; so as to prevent smearing the paint into the case, and also to further aid in providing an air-tight enclosure for the bristle portion thereof 30 within this case.

This invention thus provides means for preserving a paint brush with the paint thereon, for an extended length of time, and overcomes the former necessity of cleaning 35 out the brush every time it is laid aside; and this form of case is made of sheet metal, or the like, and is thus constructed at a very small cost.

I claim as my invention:

40 1. A case for preserving the bristle portion of a brush therein, said case comprising two members hinged together and containing wall means thereon adapted to overlap, there being an opening provided in the overlapping 45 wall means for receiving the brush handle therein, and the wall means of one of said members being bent along its edge to form a clamping channel, and compressible strip means clamped in said channel and overlapping 50 the edge of said channelled wall means, so as to be compressed between the two wall means for providing a substantially air-tight case.

55 2. A substantially wedge-shaped case for preserving the bristle portion of a brush therein, said case comprising an upper member and a lower member, which have overlapping wall means thereon including an end wall and substantially triangular side walls 60 on each member, said members being hinged together at the thin edge of the case and each having a notch in the end wall for together receiving the brush handle therein, the edge part of the wall means of one of 65 said members being bent to provide channel

means, compressible strip means clamped along its edge in said channel means and being folded over said edge part of said channelled wall means to extend between the two wall means, and similar compressible means provided on the notch part of the other member to engage the brush handle, thereby providing a substantially air-tight case for said bristle portion of the brush.

In testimony whereof I have signed this 7 specification.

RICHARD KAMM.
